(57) **CLAIM**

The ornamental design for a flat thin screen TV/monitor automotive roof mount, as shown and described.

DESCRIPTION

FIG. 1 is a rear-bottom perspective view of a preferred embodiment of the flat thin screen TV/monitor automotive roof mount according to the present invention, illustrating the screen in a viewing position;

FIG. 2 is a rear-bottom perspective view of the flat thin screen TV/monitor automotive roof mount of FIG. 1, illustrating the screen in a stowed position;

FIG. 3 is a bottom plan view of the flat thin screen TV/monitor automotive roof mount of FIG. 1;

FIG. 4 is a rear elevational view of the flat thin screen TV/monitor automotive roof mount of FIG. 1;

FIG. 5 is a front elevational view of the flat thin screen TV/monitor automotive roof mount of FIG. 1;

FIG. 6 is a left-side elevational view of the flat thin screen TV/monitor automotive roof mount of FIG. 1;

FIG. 7 is a right-side elevational view of the flat thin screen TV/monitor automotive roof mount of FIG. 1;

FIG. 8 is a top plan view of the flat thin screen TV/monitor automotive roof mount of FIG. 1;

FIG. 9 is a rear-bottom perspective view of another preferred embodiment of the flat thin screen TV/monitor automotive roof mount according to the present invention, illustrating the screen in a viewing position;

FIG. 10 is a rear-bottom perspective view of the flat thin screen TV/monitor automotive roof mount of FIG. 9, illustrating the screen in a stowed position;

FIG. 11 is a bottom plan view of the flat thin screen TV/monitor automotive roof mount of FIG. 9;

FIG. 12 is a rear elevational view of the flat thin screen TV/monitor automotive roof mount of FIG. 9;

FIG. 13 is a front elevational view of the flat thin screen TV/monitor automotive roof mount of FIG. 9;

FIG. 14 is a left-side elevational view of the flat thin screen TV/monitor automotive roof mount of FIG. 9;

FIG. 15 is a right-side elevational view of the flat thin screen TV/monitor automotive roof mount of FIG. 9; and,

FIG. 16 is a top plan view of the flat thin screen TV/monitor automotive roof mount of FIG. 9.
